UNITED STATES PATENT OFFICE.

JOHN VAN VLECK, OF NEW YORK, N. Y., ASSIGNOR, BY MESNE ASSIGNMENTS, TO NERNST LAMP COMPANY, OF PITTSBURG, PENNSYLVANIA, A CORPORATION OF PENNSYLVANIA.

ELECTRIC GLOW-LAMP.

No. 832,984.

Specification of Letters Patent.

Patented Oct. 9, 1906.

Application filed May 9, 1899. Serial No. 716,133.

To all whom it may concern:

Be it known that I, JOHN VAN VLECK, of the city, county, and State of New York, have invented new and useful Improvements 5 in Electric Glow-Lamps, of which the following is a specification.

My invention relates to that class of electric glow-lamps in which the light is emitted from a body of refractory material which at 10 normal temperatures is a non-conductor, but which upon becoming heated to a certain point becomes a conductor and is thus rendered incandescent by the passage of the current.

15 The mode of organization of my invention consists in combining with such a non-conducting body a device for heating the same and means for throwing said heating device out of operation when said refractory body 20 shall have been rendered conducting, also means for varying the proximity of said heating device to said non-conducting body, also means for effecting the said results, or either 25 of them, automatically, and also electromagnetic means for accomplishing the same.

My invention further consists in the novel features of construction of the lamp herein described, as more particularly pointed out in the claims.

30 In the accompanying drawings, Figure 1 is a side elevation of my lamp, the inclosing globe and its holder and the shade being shown in section. Fig. 2 is a vertical section. Fig. 3 is a detail view showing the mode of attachment of the carrier for the heating device. Fig. 4 is a bottom view of said carrier. Fig. 5 shows the support for the glower provided with a detachable screw cap or cover for protecting the glower during transportation. 40 Figs. 6 and 7 are electrical diagrams showing the circuit connections. Fig. 6 exhibits the circuits and relations of parts when the lamp is out of operation and Fig. 7 when the lamp is in operation.

45 Similar letters and numbers of references indicate like parts.

The term "glower" hereinafter used for brevity means the body of normally non-conducting material which is raised in temperature by the "heater," and thus becomes a conductor and permits the passage of the electrical current which causes it to glow. The term "heater" hereinafter used means

the device whereby the glower, normally non-conducting, is elevated in temperature so as 55 to become a conductor of the electrical current.

Referring first to the electrical diagrams, Figs. 6 and 7, *a* is the glower, here shown in the form of a rod of suitable refractory material, which may be, for example, magnesia. *b* and *c* are circuit connections communicating with said glower and with any suitable source of electricity. The connection *c* includes a solenoid *d*, having a movable core *e*, 60 which carries the cross-bar *f*, from which bar depend two rods *g h*. Between the rods *g h* extends the heater *i*, which may be a coil of fine platinum wire. The heater *i* is placed in such proximity to the glower *a* that the radiation from said heater will bring said glower to a temperature to render it a conductor of electricity. As here shown, the heater surrounds the glower. The circuit connections from the heater proceed, as indicated by the dotted lines *j k*, through the rods *g h* to contact-points *l m*, which are on the under side of the cross-bar *f*. Below the contact-points *l m* and secured upon a fixed support, hereinafter to be described, are 70 two spring-clips *n o*, each adapted to receive one of the contact-points *l m*. The clip *n* is electrically connected to the connection *b*. The clip *o* is electrically connected to a branch connection *p*, the other end of which 75 branches from the connection *c* at *q*. It will be obvious that instead of placing the contact-points *l m* on the cross-bar *f* and the clips *n o* on the fixed support I may reverse their positions, securing the contact-points 80 on the fixed support and the clips on the cross-bar.

The operation of the device is as follows: The parts being at starting in the position shown in Fig. 6, the current being established 95 proceeds from its source to the connection *c* by connection *p* to clip *o*, thence to the contact-point *l*, which is normally in said clip, to the connection *q*, to the heater *i*, connection *k*, contact-point *m*, clip *n*, and return connection *b*, or vice versa. The current does not originally pass by way of the glower *a*, because said glower is a non-conductor. By reason of this passage of the current through it the heater *i* is brought to a high temperature, and its heat is radiated to the glower *a*.

until the temperature of said glower becomes sufficiently elevated to enable it to conduct the current. Then the circuit proceeds from connection *c*, through the coil *d*, to glower *a* and to return connection *b*. The solenoid *d* is thus energized and caused to draw its core *e* inward and upward. The core *e* carries the cross-bar *f* with it, so drawing the contact-points *l m* out of the clips *n* and *o* and breaking circuit at these places, while also moving the heater into the position shown in Fig. 7 and above the glower. The glower now becomes brightly incandescent, while the heater is cut out and also moved out of the path of the light-rays proceeding laterally and downwardly from the glower. The parts remain as thus described and as shown in Fig. 7 as long as the lighting-current is maintained. When it is shut off, the solenoid is deenergized, the core drops, and the parts resume the position shown in Fig. 6.

I will now describe the features of construction of my lamp as shown in Figs. 1 to 5, inclusive, premising that the relative position of the parts in Figs. 1 and 2 is that which they assume when the lamp is in operation or as shown in Fig. 7. 1 is a metal tubular socket internally threaded at its upper portion to enable it to be secured to the lamp fixture or support. The inner periphery of the socket, near its lower opening, is also threaded to receive the cylindrical inclosing case 2. Between the upper edge of the case 2 and a shoulder within the socket is received the upper flange 3 of the bobbin which supports the coil *d*. Secured to the flange 3 by the screws 6 (dotted lines) is a bar 7, of insulating material, having binding-screws 5 and 8, to one of which, 5, is connected the leading-wire *b*. The other binding-screw 8 may have a return-wire connected to it; but in the present instance the case of the lamp is grounded, as will hereinafter be described, and therefore the binding-post 8 is not used. Within the coil-bobbin is the core *e*, to the outer end of which is secured by the screw 9 (dotted lines) the cross-bar *f*, of insulating material. Secured to said cross-bar are the metal rods *g h*, here also serving as the connections *j k* of Figs. 6 and 7. On the under side of the cross-bar *f* are two metal plates 11 and 12, through which the rods *g h* pass and which are secured in place by the nuts 13 and 14 on said rods. The plates 11 and 12 carry the contact-points *l m*. The rods *g h* extend through openings in the fixed support 15, of insulating material. This support 15 lies in a flanged collar 16, which is screwed upon the lower end of the cylindrical case 2. Beneath the support 15 and between the same and the lower flange 17 of said collar is the flange 18 of a tubular socket 4, through openings in which the rods *g h* also pass. On the upper side of the support 15 are the metal spring-clips *o n*, and from clip *n* a wire 20 extends

through said support and terminates in a spiral spring 22. Another wire 19 also extends through support 15 and terminates below in a similar spiral spring 21. 23 is a cylinder, which may be of insulating material, having on its upper side metal contact-plates 24 25. Metallic conductors 26 27 extend from these plates through the cylinder 23. They then pass through supporting-rods 28 and 29 and carry between them the glower *a*. The cylinder 23 fits in the socket 18 and can be readily inserted and removed. It is provided on its periphery with a fixed stud or pin 30, Fig. 1, which when the cylinder is introduced into the socket passes through the vertical portion of a slot 31 therein. The cylinder is then rotated to bring the pin into the horizontal portion of the slot, and is thus detachably secured in place, and is so shown in Fig. 1. When the cylinder 23 is thus adjusted, the contact-plates 24 and 25 bear against and slightly compress the springs 21 and 22, so that electrical circuit is thus made from the wires 19 and 20, through the conductors 26 and 27, to the glower *a*. 32, Figs. 3 and 4, is a carrier-bar, of china or other suitable insulating material, having an opening 33. Extending through this bar near each extremity are metal pins 34 and 35, each of which terminates above the bar in a spring-clip 36 37. Surrounding the pins 34 and 35 and below the bar 32 are corrugated sleeves 38 39, of insulating material. The pins receive the metal washers 40 41 42 43. The sleeves are secured in place by nuts 44 45, applied to the threaded lower ends of the pins. The heater *i* is a coil of fine platinum wire which is wound around the sleeves 38 and 39 so that its parts lie in the corrugations thereof. One terminal of the coil may connect, for example, to the metal washer 40 on pin 34 and the other terminal to metal washer 42 on pin 35. The washers 40 41 42 43 may be permanently secured to the sleeves 38 and 39. The lower ends 46 of the rods *g h* are enlarged and globular in form, so as to enter and be grasped by the spring-clips 36 37. In this way the carrier 32, with its associated parts, is detachably supported upon the lower ends of said rods. Referring now to Figs. 1 and 2, the lower portion of the periphery of the flanged collar 16 is threaded to receive the globe-supporting socket 47. Between the upper edge of this socket and a flange on the collar 16 is held the ring 48, in which the reflecting-shade 49 is secured by set-screws, as 50, in the usual way. The globe-socket is provided with air-openings 51, and the globe 52 may be secured to said socket by cement or any other suitable means. In the globe 52 I provide an opening 53, through which air may enter and subsequently escape through the ventilating-openings 51. On the exterior of the cylinder 23 is shown a

screw-thread 54, the purpose of which is to receive a screw-cap 55, Fig. 5, the purpose of which cap is to protect the glower during transportation. The electrical connections in the specific form of lamp described are to be made in any suitable way in accordance with the explanation already given and the diagrams, Figs. 6 and 7. Specifically they may be traced on Fig. 2 as follows: by wire *c* to binding-post 5, through the core to wire 19, which passes through the block 15, to spring 21, contact-plate 24, wire 26, glower *a*, wire 27, contact-plate 25, spring 22, wire 20, clip *n*, and wire *b* to the inclosing case, which is grounded, also from binding-post 5, by branch wire *p*, to clip *o*, point 7 when in said clip, plate 11, rod *g*, pin 34, washer 40, heater *i*, washer 42, pin 35, rod *h*, plate 12, pin *m*, clip *n*, and wire *b* and to ground as before.

20 The operation of this lamp is as already explained in connection with the diagrams. The rods 28 and 29, carrying the glower, extend down through the opening 33 in the carrier-bar 32, so that said glower lies normally within the heater-coil. The current first raises the temperature of the heater, and when the heater in turn raises the temperature of the glower sufficiently for the current to pass then the carrier-bar 32 is automatically raised, bringing the heater above the glower, so that the light-rays of the latter are unobstructed below and for a certain distance above a plane passing through its longitudinal axis.

35 I will now point out certain advantageous results achieved through this construction.

First. The bar 32, with the heater carried thereby, is readily removable from the rest of the lamp by simply drawing the spring-clips 36 and 37 from the globular ends 46 of the rods *g* *h*. The heater *i*, with its supporting-sleeves 38 and 39, can be taken off the pins 34 and 35 by removing the nuts 44 and 45. The pins 34 and 35 can readily then be drawn out of the cross-bar 32. This arrangement permits of the removal of the heater for packing during transportation and also the easy substitution of a new heater for one that may have become injured or the replacement of any other portion associated with the heater.

Second. The cylinder 23, carrying the glower, is readily removable from the socket 4, so as to permit of the substitution of a new cylinder and glower when desired. The protecting-cap 55 may be applied to the cylinder either while it remains in the socket 4 (the bar 32 being removed) or when it is out of the socket.

6c Third. By removing the collar 16 the block 15 and cylinder-socket 4 become free.

Fourth. The upper socket 1 is easily detachable to expose the solenoid.

In brief, the entire construction is such that all the parts are easily taken asunder to permit of repairs or substitutions and to promote economy of manufacture.

I claim—

1. The combination in an electric lamp, of the solenoid *d*, the core *e*, the rods *g* and *h* supported by said core, carrier-bar 32 carried by said rods and having an opening 33, heater *i* carried by the said carrier-bar, and fixed glower *a* extending through said opening.

2. The combination in an electric lamp, of the solenoid *d*, the core *e*, rods *g* and *h* supported by the said core, carrier-bar 32 carried by said rods and having an opening 33, the heater *i* in coil form supported by said carrier-bar, and the fixed glower *a* extending through said opening and into said heater-coil.

3. The combination in an electric lamp of the type herein specified, of the longitudinally-movable rods *g* and *h*, carrier-bar 32 detachably secured thereto, and a heater carried by said bar.

4. The combination in an electric lamp of the type herein specified, of the carrier-bar 32, pins 34 and 35 therein, insulating-sleeves 38 and 39 on said pins, and a heater-coil *i* carried by said sleeves.

5. The combination in an electric lamp of the type herein specified, of the rods *g* and *h*, having enlarged ends, 46, carrier-bar 32, spring-clips 36 and 37 on one side of the said bar adapted to receive said enlarged ends, and a heater *i* carried on the other side of said bar.

6. The combination in an electric lamp, of the socket 1, cylindrical case 2, flanged collar 16, the solenoid *d* having the core *e*, carrier-bar *f* supported by the said core, block 15, rods *g*, *h*, extending from said bar through openings in said block, the heater *i* carried by said rods *g*, *h*, and the tubular socket 4 receiving the cylindrical support 23, and the glower *a* carried by said support, and circuit connections.

7. In combination with a support, a fixed glower carried thereby, and a detachable heater surrounding said glower, a cap adapted to fit upon said support and cover said glower when said heater is removed, substantially as described.

8. In an electric lamp of the type herein specified, a heater, a detachable support therefor and means for detachably securing said heater to said support, substantially as described.

JOHN VAN VLECK.
